SIGNALING APPARATUS

Addie Good, Hicksville, Ohio

Application March 5, 1929, Serial No. 344,136

4 Claims. (Cl. 177—327)

This invention relates to improvements in signaling apparatus, especially for automobiles. The object of the invention is to provide an appliance to simulate the signals ordinarily made by the hand of the driver of a vehicle, and which is operated electrically and controlled by a simple switching means.

This object is accomplished by the construction illustrated in the accompanying drawings, 10 in which:—

Fig. 1 is an elevation of part of a construction embodying the invention, a portion being in section, the signal member being in its extreme extended position;

Fig. 2 is a similar view with the signal member in an intermediate position, and including the control members;

Fig. 3 is another view of the appliance showing the signal member in another of its positions, 20 and also with the signal member dotted in its normal position;

Fig. 4 is a bottom plan view of the housing of the appliance;

Fig. 5 is a detail view of one of the control 25 members for the signal extending device;

Fig. 6 is a fragmentary view of the appliance showing the stops and the signal extending device related therewith;

Fig. 7 is an end view projected from Fig. 6;

Fig. 8 is a diagram showing the related members of the signal appliance and the electrical connections therefor; and

Fig. 9 is a detail view drawn upon an enlarged scale showing a cross-section of the supporting 35 arm for the signal member.

The invention consists of a signal member 1 preferably in the form of a human hand constructed of translucent material such as celluloid or glass, and in which member is mounted in any 40 suitable manner an electric lamp 2 by which said member is illuminated.

The signal member 1 has a pivot 3 supported in a bearing 4 that is fixed on a tubular arm 5, and said pivot 3 has fixed thereon a pinion 6 45 which has engagement with a rack-bar 7 located within the tubular arm 5 in which it is longitudinally movable and whereby rotary movement is imparted to the signal member through the medium of said pinion.

The tubular arm 5 is supported upon the outer 50 end of a lazy tong 8, and the rear end of said rack-bar has a slotted head 9, through a slot of which extends the pin 10 that forms a pivot for the lazytong at a point spaced from the 55 outer end thereof.

The inner end of the lazy tong 8 has oppositely projecting trunnions 11 that extend through the corresponding sides of a housing 12, and said lazytong has a transversely disposed pin 13, the ends of which project into and have sliding movement in slots 14 made in the corresponding sides of said housing. The lazytong is sustained by said trunnions and pin in said housing so that limited longitudinal movement of the lazytong relative to the housing is permitted, said slots 14 serving as guides for the pin 13.

Upon the rear end of the housing is mounted a pneumatic member consisting of a cylinder 15 having a plunger 16 therein, said plunger having a rod 17 provided with a hook 18 that is connected with said transverse pin 13, so that when said plunger is reciprocated in the cylinder, said lazytong is extended or contracted accordingly.

Upon the exterior of the housing 12 is mounted a valve-case 19 having valves 20 and 21 disposed therein that are oppositely operated by a T-shaped lever 22 which is pivotally mounted in connection with said valve-case. The valve-case has communication with a tube 23 that is connected with a suitable source of 75 vacuum (not shown) such as the intake manifold of an automobile engine, and the valves 20 and 21 are operatively related with the rear and forward ends of the cylinder 15 respectively and the tube 23 whereby said plunger is caused 80 to move in one direction or the other accordingly as said valves are actuated. The forward end of the cylinder 15 is related with the valve 21 through a connection 24, and the rear end of said cylinder is related with the valve 20, 85 through connections 25 and 26. By operation of said valves vacuum is applied selectively to the corresponding ends of said cylinder so that said lazy tong is thereby projected outwardly or contracted.

The pin 10 in the lazytong has limited sliding movement in the slotted head 9 of the rack-bar 7, so that the lazytong is projected outwardly to the position shown in Fig. 3 without causing relative movement between said rack-bar and the tubular arm 5. However, the slot 9' in said head is so proportioned that when the lazytong is moved to the extent shown in Fig. 2, the rack-bar 7 is moved in the arm 5 105 so that the signal member 1 is turned to a corresponding extent, and when the lazytong is moved to the extent shown in Fig. 1, said signal member 1 is turned to a further extent. Also, when the lazytong is completely contracted said 110

signal member is returned to its initial position as indicated by dotted line in Fig. 3.

Upon the housing 12 is mounted a solenoid 27 having a plunger 28 that is operatively related 5 with the lever 22 through the medium of an arm 29, whereby when the solenoid is energized the plunger is raised and said lever is tilted and the valves 20 and 21 actuated accordingly. In this manner vacuum is applied through the 10 connection 24 to the front end of the cylinder 15, and the rear end of said cylinder is vented through the connection 25, and thus the plunger 16 is moved to its forward position and the lazytong is extended thereby. When the supply 15 of current is turned off from the solenoid 27, the plunger 28 and the valves 19 and 21 re- 20 lated therewith return to their normal positions. Thus vacuum is applied to the rear end of the cylinder 15 through the connection 25 and the forward end of said cylinder is vented through the connection 24 so that the plunger 16 is moved rearwardly causing contraction of the lazytong. The valve-case and the valves therein 25 may be of any suitable construction such as are in common use for the similar purpose of actuating the plunger, and are not shown in detail as their particular form is immaterial to the present invention.

As a means to limit the extension of the lazytong at different stages two stops 30 and 31 are disposed in a guide 32 on the exterior of the housing beneath the slot 14 and disposed so as to have engagement, when elevated, with the adjacent end of the pin 13 on the lazytong, 35 and thus interrupt the forward sliding movement thereof in said slot. The stop 30 is operatively related with the plunger 33 of a solenoid 34 mounted on said housing so that when said solenoid is energized the stop 30 is elevated, 40 there being an arm 35 connecting said plunger 33 and stop 30. The stop 31 is operatively related with a plunger 35 of a solenoid 36 mounted on said housing so that when said solenoid is energized the stop 31 is elevated, 45 there being an arm 37 connecting said plunger 35 and stop 31.

The lamp 2 in the signal member 1 is supplied with current through a conductor 38, preferably having connected in line therewith a resistance member 38' with which conductor the solenoid 50 27 is in circuit, said conductor being controlled by a switch 39, the conductor 38 is supported by the lazytong 8 at various points thereon so as to fold within the housing 12 when the lazytong is contracted. The solenoid 34 is supplied with current through a conductor 40 controlled by a switch 41, the solenoid 34 being connected in the circuit with the solenoid 27 and lamp 2. The solenoid 36 is energized 55 through a conductor 42 controlled by a switch 43, said solenoid 36 being connected in circuit with the solenoid 27 and lamp 2. The conductors 38, 40 and 42 have connection with one of the terminals of a battery 44 from which current therefor is supplied, the other terminal of said battery being grounded as indicated by 45. Also, one terminal of the lamp 2 is grounded as indicated by 46.

The switches 39, 41 and 43 may be of any 70 suitable type, and the electrical connections for controlling the solenoids and the lamp may be arranged in any suitable manner to effect proper operation of the apparatus, the diagram being shown as an example.

75 In utilizing the invention, the housing is

mounted upon the body of a vehicle, by means of brackets 47 attached thereto, in such position that when the lazytong is extended, the signal member will be exposed to view from the rear and the front of the vehicle, and the switches are positioned in the vehicle conveniently accessible to the driver. When a left hand turn is contemplated the driver closes the switch 41 causing the solenoids 34 and 27 and the lamp 2 to be energized, whereupon the stop 30 is raised to engaging position and the valve 21 is opened so that the plunger is drawn forwardly and the lazytong is extended to the position limited by said stop as indicated in Fig. 3. When a right hand turn is contemplated, 80 the driver closes the switch 39 causing the solenoid 27 and the lamp 2 to be energized, whereupon the valve 21 is opened so that the plunger is drawn forwardly and the lazytong is extended to its outermost position as indicated 85 in Fig. 1, its outward movement being limited by the pin 13 upon reaching the end of the slot 14. The rack-bar 7 being withheld by engagement with the pin 10 while the tubular arm is projected farther, causes rotation of the pinion 6 and consequent turning of the hand. When a stop or material reduction in speed is contemplated, the switch 43 is closed by the 90 driver, causing the solenoids 36 and 27 and the lamp 2 to be energized, whereupon the stop 31 is 95 raised to engaging position and the lazytong is extended to a position limited by contact of the pin 13 with said stop as indicated in Figs. 2 and 6. In each instance, upon opening of the 100 switch the current through the solenoid 27 and lamp 2 ceases, whereupon the plunger 28 of said solenoid 27 gravitates to its normal position and actuates the lever 22 so that the valve 20 is opened and the plunger is drawn to the rear end of the cylinder causing the lazytong to 105 fold within the housing and the hand to be turned to the position shown in dotted outline in Fig. 3.

The signal member is illuminated by the lamp when moved to extended position and thus 110 indicates that the signal is active. The position of the hand which constitutes the signal member, when the fingers are pointed downwardly, as in Fig. 3, is significant of the intention of the driver to make a left hand turn. The hand, 115 when extended horizontally, as in Fig. 2, is significant of the driver's intention to stop or materially reduce the rate of travel. The hand when positioned with the fingers extending upwardly, signifies the intention of the driver to 120 make a right hand turn.

What I claim is:—

1. A signal apparatus for an automobile consisting of an arm; a mechanism for supporting and imparting longitudinal movement to said arm; stops for limiting said movement of said mechanism at different stages thereof; a signal member provided with a pinion pivotally supported in said arm; a rack-bar in mesh with said pinion, an operative connection between 135 said arm and rack-bar to cause relative movement therebetween when the arm is actuated, whereby said member is turned upon its axis to different positions during corresponding positions of said movement; and means for actuating 140 said mechanism and stops.

2. A signal apparatus for an automobile consisting of an arm, a mechanism supporting and imparting longitudinal movement to said arm, stops for limiting movement of said arm, a sig- 145

nal member provided with a pinion pivotally supported in said arm, a rack-bar in mesh with said pinion, an operative connection between said arm and rack-bar to cause relative movement therebetween when the arm is actuated, whereby turning movement is imparted to the signal member upon its axis to different signaling positions as the arm is extended, actuating means for said arm, and electrical means 10 for selectively controlling said stops.

3. A signal apparatus for an automobile consisting of a lazytong, an arm supported at the outer end of said lazytong, stops for limiting movement of said lazytong at different stages 15 of its movement, a signal member provided with a pinion pivotally supported in said arm, a rack-bar in mesh with said pinion, an operative connection between said lazy-tong and rack-bar to

cause relative movement therebetween when the lazy-tong is actuated, for imparting relative movement thereto whereby the member is turned upon its axis to different signaling positions, actuating means for said mechanism, and 80 electrical means controlling said stops.

4. A signal apparatus for an automobile consisting of a lazytong, an arm extending from the outer end of said lazytong, stops for limiting movement of said lazytong at different stages thereof, a signal member pivoted on said arm, actuating means for said member adapted to turn it upon its axis to different signaling positions as the arm is moved to different stages, and actuating means for said lazytong and 90 stops.
